UNITED STATES PATENT OFFICE.

GEORGE J. KOCHALEK, OF AVOCA, PENNSYLVANIA.

WATER-BOMB.

1,272,461.

Specification of Letters Patent. Patented July 16, 1918.

Application filed March 20, 1918. Serial No. 223,506.

To all whom it may concern:

Be it known that I, GEORGE J. KOCHALEK, a citizen of the United States of America, residing at Avoca, in the county of Luzerne and State of Pennsylvania, have invented 5 certain new and useful Improvements in Water-Bombs, of which the following is a specification.

The primary object of the invention is the provision of a bomb adapted to be dropped from an elevated position such as an aeroplane, the device being especially serviceable in bombing water-craft such as a submarine.

15 A further object of the invention is to provide an aerial bomb adapted for readily moving through the water when dropped from an aeroplane at a submerged boat and adapted to automatically explode upon striking the boat, the device being formed in separable sections for ease in transportation and readily assembled when required for use.

A still further object of the device is the provision of a bomb arranged for steering 25 and firing and having an explosive member secured in its operative arrangement by assembling the device with the steering and firing means detachably connected together.

In the drawings forming a part of this 30 application and in which like numerals refer to corresponding parts throughout the several views:

Figure 1 is a side elevation of the complete device;

35 Fig. 2 is a longitudinal central sectional view of a portion thereof with the steering means shifted for permitting the insertion of the explosive body;

Fig. 3 is a perspective view of the main 40 double wing employed with the steering mechanism;

Fig. 4 is a similar view of one of the single wings employed therewith;

Fig. 5 is a top plan view of the device; 45 and

Fig. 6 is a top plan view of the mounting means for the steering and the explosive members.

Referring more in detail to the drawings, 50 the device broadly consists of a conical weight 10 having a sleeve 11 mounted upon the cylindrical base end 12 thereof while the explosive body or bomb 13 is retained within the free end of the sleeve 11 by means of 55 a steering device that is detachably connected to the sleeve 11.

Oppositely arranged bayonet-slot connections 15 are provided between the sleeve 11 and base 12 while a partition 16 is provided in the sleeve having a central opening 17 through which a firing pin 18 is adapted to be projected when the lower free end 19 of the said pin projecting outwardly of the pointed end 20 of the weight strikes an object during the travel of the device. The firing pin 18 is slidably arranged axially 60 through the weight 10 having a spring 21 normally positioning the pin with its pointed inner end 22 spaced from the perforation 17 when the device is assembled.

The bomb 13 carries a stem 23, which has a resilient strap 24, adapted for seating upon opposite ledges 25 provided within the sleeve 11, while an explosive cap 26 is carried by the free end of the stem 23 overlying the 70 perforation 17.

The steering means consists of four wings 27 in the form of semi-circular plates positioned in perpendicular arrangement, and having cutaway portions 28 for accommodating the explosive body 13 when the wings 80 are mounted thereover with the lower extremities of the wings connected to side lugs 29 of the sleeve 11 by means of links 30. Two of the wings 27 are preferably formed 85 integral in substantially circular arrangement as shown in Fig. 3 of the drawings, radial openings 31 being provided therein adapted for the reception of fingers 32 of the other wings 27 therethrough.

In this manner, two of the semi-circular wings will be diametrically secured to the semi-circular wing in perpendicular relations as best shown in Fig. 5 of the drawings, the two semi-circular wings being laterally 95 shifted upon the circular double wing by means of the fingers 32 after the manner of a hinge permitting the explosive body 13 to be positioned within the cutaway portions 28 of the wings and with the explosive body 100 supported on the strap 24 mounted upon the ledges 25 when the links 30 are connected with the lugs 29.

The strap 24 being resilient retains the explosive member 13 in engagement with the 105 edges of the wings at the cutaway portions thereof when the device is assembled as illustrated in Fig. 1 of the drawings. The fingers 32 are readily bent for maintaining the wings in their perpendicular relations after 110 the device is assembled, as shown in Fig. 5. The device is readily assembled in the man-

ner heretofore noted, the separate parts thereof being easily transported when disassembled and the operation of the complete device will be apparent in that the striking 5 of the free end 19 of the firing pin against any object projects the pointed inner end 22 of the pin through the perforation 17 for exploding the cap 26 and causing the body 13 to explode wherever the same is positioned, 10 such for instance as beneath the surface of the water when the device strikes a submarine. The wings 27 direct the device in a straight course when dropped through the air while the weight 10 causes the device to 15 rapidly descend, the conical form thereof causing the device to readily penetrate and pass through the water, steered therethrough in a straight course by means of the aforementioned wings 27.

20 What I claim as new is:—

1. A device of the class described comprising a conical weight, a sleeve detachably connected to the base end of said weight, a bomb supported at the upper end of the said 25 sleeve, steering wings attached to the sleeve arranged in overlying restraining relations with respect to the bomb when the device is assembled, and automatic firing means for the bomb.

30 2. A device of the class described comprising a conical weight, a sleeve detachably connected to the base end of said weight, a bomb supported at the upper end of said sleeve, steering wings attached to the sleeve 35 arranged in overlying restraining relations with respect to the bomb when the device is assembled, hinge connections between the said wings whereby the wings are adapted for relative shifting movement during the 40 assembling of the device, the said wings being arranged in perpendicular arrangement when the device is assembled, an exploding cap for the bomb arranged within the sleeve, and a firing pin for the cap axially positioned through the weight adapted for longitudinal movement in the plane of said cap 45 when the forward end of the device strikes an object during the forward travel of the same.

50 3. A device of the class described providing a conical weight, a sleeve overlying the

larger end of the weight, bayonet slot connections between the sleeve and weight, a partition within the sleeve having a central perforation, oppositely positioned ledges arranged within the sleeve, an explosive bomb 55 extending into the sleeve, a firing cap for the bomb arranged over said perforation, automatic firing means for the cap having a path of movement through the said perforation, and steering means for the device retaining the bomb in position and attached to the sleeve.

4. A device of the class described providing a conical weight, a sleeve overlying the 60 larger end of the weight, bayonet slot connections between the sleeve and weight, a partition within the sleeve having a central perforation, oppositely positioned ledges arranged within the sleeve, an explosive bomb 65 extending into the sleeve, a firing cap for the bomb arranged over said perforation, automatic firing means for the cap having a path of movement through the said perforation, substantially circular wings adapted for relative movement during the assembling of the 70 device having cutaway portions for overlying the said bomb when the device is assembled, connections between the said wings and sleeve, and a resilient strap seated upon 75 said ledges and in contact with the bomb at the opposite end thereof from the points of engagement of the wings with the said bomb.

5. In combination with a weight, sleeve mounted thereon, a substantially circular 80 double wing member secured diametrically with respect to the sleeve and having a cutaway portion adjacent the open end of the sleeve, a bomb arranged within said cutaway portion and extending into the sleeve, 85 automatic exploding means for the bomb, substantially semi-circular wings hinged to the said double wing adapted for relative swinging movement with respect to said double wing after the insertion of the bomb, 90 the said semi-circular wings having cutaway portions adapted for overlying the bomb 95 when the device is assembled with the wings in perpendicular arrangement, and connections between the said wings and sleeve.

In testimony whereof I affix my signature.
GEORGE J. KOCIALEK.
